TELEPHONE SYSTEM

Clarence Ernest Lomax, Oak Park, Ill., assignor
to Associated Electric Laboratories, Inc., Chi-
cago, Ill., a corporation of Delaware

Application May 27, 1938, Serial No. 210,378

18 Claims. (Cl. 179—39)

The present invention relates to telephone systems and more particularly to improvements in telephone systems of the intercommunication type.

5 A system of the character mentioned is usually divorced from all central exchange equipment and is used for communication between the offices of a small organization. In the usual arrangement, a plurality of lines are provided which individually correspond to the telephone stations of the system and individually extend to all of the telephone stations. A line selecting switch is provided at each station for selectively associating the telephone set at the station with any 10 one of the several lines. In the usual arrangement of this character, when a call is initiated at any station, the signal device provided at that station is rendered inactive so that it can not be energized until the established connection is 15 cleared out. In at least one system of the character described, the arrangement is such that the lines are used only on calls incoming to the corresponding stations, the switching apparatus at each station being so arranged that, when the 20 telephone receiver or subset at a particular station is removed from its supporting hook or cradle, the telephone transmitter and receiver at the particular station are connected to the home line or the line corresponding to the particular 25 station. With this latter type of system, a call is initiated at any station by first operating the line selecting switch provided at that station to a particular position corresponding to a desired line and then operating special switching apparatus which functions to cause the operation 30 of the signal device provided at the called station and also to connect the transmitter and receiver at the calling station to the line corresponding to the position of the line selecting 35 switch.

It is an object of the present invention to provide an improved system of the character described which is of simple and economical arrangement and is so arranged that calls may be 40 initiated at the telephone stations in a simplified manner.

It is another object of the invention to provide a system of the character described wherein a line selecting switch is provided at each station for selecting stations to be called and wherein a single additional switch is provided at each 45 station, which additional switch is operable to answer incoming calls and is operable to perform all switching functions incident to the estab-

lishing of connections to stations selected by the associated line selecting switch.

It is a further object of the invention to provide a system of the character described wherein the additional switch provided at each station is 5 operable to perform certain of its switching functions in response to the removal of the associated receiver from its supporting hook or cradle.

It is still another object of the invention to provide a system of the character described 10 wherein talking battery or current for energizing the transmitters used at the two ends of an established connection is connected to the line involved in the connection in an improved manner.

It is a still further object of the invention to provide a system of a character described which is arranged in an improved manner such that the signal device at each station is not rendered inactive when a call is initiated at the 20 corresponding station.

The invention is illustrated as being incorporated in an intercommunicating system comprising a first station including a transmitter and receiver and arranged to be interconnected with a plurality of additional stations by lines individually extending to all of the stations and individually corresponding to the stations. Each of the lines is adapted to be used only on calls incoming to the corresponding station. There is provided at the first station a line selecting switch which is operable to a plurality of positions individually corresponding to the station lines to select the lines for use on calls to the stations corresponding thereto. In accordance 30 with one feature of the present invention, a second switch, having a plurality of operating positions, is provided at the first station, together with means responsive to the operation of the second switch to one of its operating positions for 35 connecting the transmitter and receiver at the first station to be used in communicating over the line corresponding to the first station irrespective of the position of the line selecting switch at the time the second switch is operated, 40 and means operative in response to operation of the second switch to another of its operating positions for connecting the transmitter and receiver to be used in communicating over the line corresponding to the position occupied by the 45 line selecting switch. In the illustrated embodiment of the invention, the second switch is arranged to be operated to its one position in response to removal of the telephone receiver provided at the first station from its supporting hook 50 55

or cradle. This second switch is preferably of the form disclosed and claimed in the copending application, Serial No. 210,348, Herbert F. Obergfell, filed May 27, 1938. The normal position of the second switch is the position assumed thereby when the receiver provided at the first station is replaced upon its supporting hook or cradle, means being provided, operative in response to operation of this switch to its normal position, for disconnecting the transmitter and receiver at the first station from all of the lines. A signal device is provided at each of the telephone stations embodied in the system and, in accordance with a further feature of the invention, means, responsive to operation of the above-mentioned second switch, are provided for causing the operation of the signal device located at the station corresponding to the position occupied by the line selecting switch of the first station. The arrangement is such that the signal device provided at the first station is only rendered inactive when the second switch mentioned above is operated to its one position to answer a call incoming to the first station. By this arrangement, it is possible to signal the station even though the station is involved in an established connection, when the established connection results from a call initiated at the first station. In accordance with a further feature of the invention, means are also provided, operative in response to operation of the second switch to its one or answering position, for connecting a current supply source to the line corresponding to the first station for the purpose of energizing the transmitters used in an established connection including this line.

Further features of the invention pertain to the particular arrangement of the circuit elements whereby the above and additional operating features are attained.

The novel features believed to be characteristic of the invention are set forth with particularity in the appended claims. The invention, both as to its organization and method of operation, together with further objects and advantages thereof, will best be understood by reference to the drawings wherein Figure 1 is a cross-sectional view of a fragment of a subset having embodied therein a switch constructed and arranged in accordance with the invention disclosed and claimed in the above-referred to copending application, Figs. 2, 3 and 4 illustrate different operating positions of the switch shown in Fig. 1; Figs. 1a, 2a, 3a and 4a illustrate the arrangement of the switch contacts when the switch occupies the positions respectively shown in Figs. 1, 2, 3 and 4; Fig. 4b is a bottom view illustrating the contact controlling mechanism of the switch when the switch occupies the position shown in Fig. 4; and Fig. 5 illustrates the circuit arrangement of a circuit connected and arranged in accordance with the present invention.

Referring now more particularly to Figs. 1 to 4b of the drawings, the improved switch referred to above is illustrated as being mounted within a pedestal or base 10 of a telephone subset of the hand set type. The pedestal 10 is provided with upstanding lugs or arms, two of which are indicated at 11, which are displaced in the usual manner to provide a cradle for supporting therein the handle portion of the hand set diagrammatically indicated at 12. The contacts and controlling mechanism therefor are carried by a bracket member 13 which is secured to the top

portion 14 of the pedestal 10 by a mounting arrangement comprising spacing members 15 and screws 16. More particularly, each of the screws 16 extends through openings provided in the bracket 13, the associated one of the annular spacing members 15 and the top portion of the pedestal 10, and is threaded into a tapped cap 17 which forms a rest for the handle of the hand set 12.

The switch comprises an operating member in the form of a plunger 18 having a plurality of operating positions illustrated, respectively, in Figs. 1 to 4, inclusive, of the drawings, and a contact controlling member comprising an element 19 pivotally mounted at 20 upon two lugs 21 projecting downward from the bracket member 13. The plunger 18 is mounted upon the upper portion 14 of the pedestal 10. More particularly, the plunger 18 is supported within a cup-shaped member 9 having an upper end of reduced cross section extending through and snugly engaging an opening provided in the top portion 14 of the pedestal 10. A nut 8, threaded onto the reduced end portion of the member 9, serves rigidly to secure this member to the portion 14 of the pedestal 10. The plunger 18 is provided with a lower portion 18a of reduced cross section which extends through an opening provided in the lower wall of the member 9. An enlarged cap 18b having a shank threaded into the lower end of the plunger 18 is provided for restricting the movement of the plunger in an upward direction. The plunger is normally biased in an upward direction toward one of its operating positions by a helical spring 7 surrounding the portion 18a of the plunger and having one end abutting the enlarged portion of the plunger and the other end abutting the lower wall of the member 9.

The contact controlling element 19 includes an arm 22 biased to engage the rounded lower surface of the cap 18b and carries two contact actuating rollers 23a and 23b rotatably mounted, respectively, upon pins 24a and 24b rigidly supported upon the element 19. These rollers, which are formed of insulating material, respectively cooperate with two different operating springs of a spring pile comprising the springs 25 to 34, inclusive. The springs 25 to 28, inclusive, are mounted upon one leg 34' of a U-shaped supporting bracket 35 rigidly secured to the bracket member 13. The springs of this group are insulated from each other by spacing members 36 formed of insulating material, and are secured to the leg 34' of the bracket piece 35 by screws 37 extending through a face plate 33 and the alternately spaced insulating members 36 and springs, and threaded into the leg 34'. A similar arrangement is used for mounting the springs 29 to 33, inclusive, upon the other leg 39 of the U-shaped bracket piece 35. The springs of the last-mentioned group are insulated from each other by members 40 formed of insulating material and are secured to the bracket leg 39 by screws 41 extending through a face plate 42 and the alternately spaced springs and insulating members, and threaded into appropriately spaced tapped openings provided in the leg 39. The springs 27, 30 and 32 of the spring pile comprise the main operating springs and are movable in response to movement of the rollers 23a and 23b carried by the contact controlling member 19. To this end, the springs 27 and 30 are formed of relatively heavy resilient stock and are respectively provided with curved end portions 75

27^a and 30^a which respectively cooperate with the rollers 23^a and 23^b. The resilient spring 32 is arranged to respond to movement of the spring 30 through the provision of an element 43 formed of insulating material and rigidly secured to the spring 32. The element 43 is biased by the spring 32 to engage the spring 30 so that movement of the spring 30 is directly transmitted to the spring 32.

10 For the purpose of locking the contact controlling element 19 in one of its operating positions, there is provided locking means comprising an element 44 pivotally mounted at 45 upon a bracket piece 46 secured by means of a screw 47 to the bracket member 13. The element 44 is provided with a recess 48 which is adapted to engage the end of the arm 22 to restrain the contact controlling member 19 in the position shown in Fig. 4. The element 44 is normally biased to move 15 in a counterclockwise direction toward the end of the arm 22 by a spring 49 connected between the lower end of the element 44 and the left end of the arm 22. This spring also serves to bias the right end of the arm 22 into engagement with the 20 lower rounded surface of the cap 18^b secured to the plunger 18. Movement of the element 44 in a counterclockwise direction is limited by a stop comprising an arm 50 forming a part of the bracket piece 46 and provided at its lower end 25 with a bent-over projection lying in the path of movement of the element 44.

30 For the purpose of releasing the locking means just described to permit the arm 22 to be moved under the influence of the spring 49 back into engagement with the cap 18^b carried by the plunger 18, there is pivotally mounted at 52 on the element 44 a finger 53 which is normally biased into engagement with a bent-over portion 54 of the element 44 by means of a light helical spring 55 having one end secured to the bracket piece 46 and the other end secured to the right end of the finger 53. As best shown in Fig. 4b, the free end of the arm 22 is cut away at 22^a to permit the arm to be moved between its two 45 extreme positions without engaging the finger 53.

With the operating member or plunger 18 occupying its normal position as shown in Fig. 1 of the drawings or, more particularly, with the hand set 12 resting upon its supporting pedestal 10 so that 50 the plunger 18 is depressed to its first intermediate or normal position, the contact controlling element 19 occupies a position such that the contact springs of the spring pile have the arrangement illustrated in Fig. 1a. It will be observed that, 55 with the contact controlling member in this position, only the springs 32 and 33 are in engagement. When the hand set is removed from its supporting pedestal 10, the spring 7 forces the plunger 18 upward to its first position so that the 60 elements of the contact controlling mechanism assume the positions illustrated in Fig. 2. More particularly, when the plunger 18 is moved upward, the arm 22 is rotated in a counterclockwise direction under the influence of the spring 49 and the rollers 23^a and 23^b are moved to the right 65 over the curved portions 27^a and 30^a respectively, of the springs 27 and 30, so that a new arrangement of the contact springs is achieved. It will be observed that the cut away portion 22^a of the arm 22 passes by the finger 53 during movement 70 of the arm 22 to the position shown in Fig. 2. During the indicated movement of the contact controlling member 19 the springs 32 and 33 are moved out of engagement, the spring 32 is moved 75 into engagement with the spring 31, the spring 30

is moved into engagement with the spring 29, and the spring 27 is moved into engagement with the spring 28.

If, with the elements of the switch occupying the positions shown in Fig. 2, the plunger 18 is depressed by pressing downward thereon, it is moved through its normal or first intermediate position as shown in Fig. 1 and the second intermediate position as shown in Fig. 4 to its final position as shown in Fig. 3. During such movement, the contact controlling element 19 is rotated in a clockwise direction against the bias of the spring 49 and the rollers 23^a and 23^b, by riding over the inwardly curved ends 27^a and 30^a, respectively of the springs 27 and 30, force the 10 springs 27 and 30 outward so that, at the end of the movement, the contact arrangement illustrated in Fig. 3a is achieved. More specifically, the springs 27, 30 and 32 are moved out of engagement with the springs 28, 29 and 31, respectively, 15 and are moved into engagement with the springs 26, 34 and 33, respectively. Also, with the plunger 18 occupying its final operating position, the spring 26 is forced outwardly into engagement with the spring 25. As the plunger 18 is moved 20 downward from its first operating position to its final position the cap 18^b engages the rounded cam surface provided on the left end of the finger 53, which finger is biased into engagement with the stop 54. Due to the engagement of the cap 18^b 25 and the finger 53, the locking element 44 is pivoted in a counterclockwise direction to move the finger out of the path of movement of the cap 18^b. When the cap 18^b is moved beyond the finger, the 30 element 44 is snapped into engagement with the right end of the arm 22 under the influence of the spring 49 and continues to engage the arm 22 until the final position of the plunger 18 is reached.

If, after the plunger 18 has been depressed to its lowermost or final operating position, it is released, it starts to move upward under the influence of the spring 7, and the contact controlling member 19, due to the force exerted thereon by the biasing spring 49, follows the movement of the plunger during a portion of its movement toward its first operating position. At this time, the lower portion of the locking element 44 is biased into engagement with the right end of the arm 22 so that, when the plunger is returned to its next to last operating position, the right end 40 of the arm 22 engages or drops into the recess 48 provided in the locking element 44 to hold the contact controlling member in a position, shown in Fig. 4, corresponding to the next to final position of the plunger 18 while the plunger returns 45 to its first operating position. During the return movement of the plunger 18 the upper side of the cap 18^b engages the finger 53 to cause this finger to be pivoted in a clockwise direction against the bias of the spring 55 out of the path of movement 50 of the cap. After the cap passes over the finger 53, the finger is rotated back into engagement with the projection 54 by the spring 55. With the contact controlling element 19 occupying the position 55 shown in Fig. 4, the contact springs 25 and 26 are disengaged, but otherwise the contact arrangement is the same as shown in Fig. 3a.

Release of the locking means to permit the contact controlling member to return to its normal position is effected when the hand set 12 is 60 again placed upon its supporting pedestal 10. Thus, when the hand set 12 is replaced upon the supporting pedestal 10, the plunger 18 is forced downward to its normal or first intermediate position by the weight of the hand set. During 65 70 75

the final movement of the plunger, the cap 18^b carried thereby engages the rounded end of the finger 53. Since this finger is now biased by the spring 55 into engagement with the projection or stop 54, the downward movement of the plunger 18 causes the locking element 44 to be pivoted in a counterclockwise direction a sufficient amount to disengage the right end of the arm 22 from the recess 48. Hence, the arm 22 is permitted to return to its normal position or into engagement with the cap 18^b under the influence of the spring 49 whereby the contact springs are caused to again assume the positions shown in Fig. 1a.

15 Referring now more particularly to Fig. 5 of the drawings, there are illustrated two telephone stations A and B of an intercommunicating telephone system connected and arranged in accordance with the present invention, which 20 stations respectively include telephone subsets of the form shown in Fig. 1. The two stations A and B and the other stations of the system, not shown, include the same apparatus connected and arranged in the same manner. For this 25 same reason, corresponding reference numerals, carrying the exponents *a* and *b*, respectively, are used to indicate corresponding elements provided at the two stations A and B. The several stations of the system are interconnected by a 30 plurality of lines including the lines 60, 61 and 62, individually corresponding to the stations and each extending to all of the stations. More particularly, the line 60 corresponds to the station A, the line 61 corresponds to the station B, and the line 62 corresponds to a third station, not shown. Considering the station A by way of example, the apparatus provided at this station comprises a transmitter 63^a, a receiver 64^a, a line selecting switch 65^a, and a signal device in the 35 form of a bell 66^a. The line selecting switch 65^a is of the well-known rotary type and may be of any standard commercial construction. Briefly described, the switch 65^a comprises two sets of contacts 67^a and 68^a, wipers 69^a and 70^a, respectively associated with the contact sets 67^a and 68^a, and a rotatable operating element indicated by the dotted line 71^a for operating the two wipers in unison. Corresponding contacts of the two sets 67^a and 68^a are respectively connected to opposite sides of the lines extending between the telephone stations of the system. Thus, the negative line conductor 60^a of the line 60 is connected to the first contact of the set 68^a and the opposite line conductor 60^b of the line 60 is connected to the first contact of the set 67^a. In a similar manner, the line conductors of the other lines are connected to the contacts of the two sets 67^a and 68^a.

60 There is also provided at the station A a second switch 72^a which is of the construction and arrangement shown in Figs. 1 to 4b, inclusive. This switch includes a plurality of contact springs 25^a to 34^a connected and arranged in an improved manner such that all of 65 the operations incident to the answering of an incoming call and to the completion of a talking connection on a call initiated at the station A may be performed by operation of the switch. For the purpose of energizing the transmitters 70 utilized in an established connection extending by way of one of the lines between two stations, there is provided a current source comprising a battery 73 which is arranged to have its opposite terminals connected to the line conductors 75 of the line 60 utilized in an established connec-

tion through the respective windings of an impedance element 74^a. The element 74^a is provided for blocking voice frequency currents to prevent such currents from flowing through the battery 73. The arrangement is such that talking battery is impressed on a line utilized in an established connection through the springs of the switch 72^a provided at a called station when the call resulting in the connection is answered at the called station. The battery 73 is commonly used for this purpose through the provision of a battery feed line comprising the two conductors 75 and 76. For the purpose of energizing the signal devices located at the respective stations, there is provided a second battery 15 77 commonly associated with all of the stations and arranged to supply energizing current to the signal device at any called station over a line comprising the conductor 75 and a third conductor 78. 20 Referring now to the operation of the system shown in Fig. 5, if it be assumed that a party at the station A desires to establish a connection to the station B, the line selecting switch 65^a is first operated to the position corresponding to the line 25 61. This is accomplished by operating the switch 65^a to a position such that the wipers 69^a and 70^a engage their respective associated second contacts. Following this operation, the hand set comprising the transmitter 63^a and the receiver 30 64^a is removed from its supporting cradle and the operating member or plunger of the switch 72^a is manually depressed to its lowermost or final position. In response to the operation of the operating plunger of the switch 72^a to its final 35 position, a circuit is completed for energizing the signal device 66^b provided at the called station B. This circuit may be traced as extending from one terminal of the battery 77 by way of the line conductor 75, the winding of the signal device 66^b, the resting contacts 33^b and 32^b of the switch 72^b, the line conductor 61^b, the second contact of the set 67^a, the wiper 69^a, the contacts 26^a and 25^a and the conductor 78 to the other terminal of the battery 77. By repeatedly operating the plunger of the switch 72^a to its lowermost or final position the signal device 66^b may be energized to signal the called station as many times as desired. 40

When the plunger of the switch 72^a is released 50 after being depressed one or more times to its final position, the locking means described previously operates to hold the contact controlling element of the switch in its next to final position so that the spring 27^a engages the spring 26^a, the spring 30^a engages the spring 34^a, and the spring 32^a engages the spring 33^a. During movement of the operating plunger of the switch 72^a from its final position to its next to final or last intermediate position, the contact springs 25^a and 26^a 60 are moved out of engagement to open the above-traced circuit for energizing the signal device 66^b provided at the called station. With the contacts 26^a and 30^a respectively engaging the contacts 27^a and 34^a, the transmitter 63^a and the receiver 64^a provided at the substation A are connected to be used in communicating over the line 61 corresponding to the called station B and to the position occupied by the line selecting switch 65^a. More particularly, one terminal of 70 the subset is connected by way of the springs 30^a and 34^a, the wiper 70^a and the second contact of the set 68^a to the negative line conductor 61^a of the line 61, and the other terminal of the subset is connected by way of the contact springs 27^a 75

and 26^a, the wiper 69^a and the second contact of the set 67^a to the opposite line conductor 61^b of the line 61. It will be observed that, with the switch 72^a occupying its last intermediate position, the springs 31^a and 32^a are out of engagement so that the battery 73 is not connected to the conductors of the line 61 through the switch 72^a provided at the calling station.

The call is answered at the called substation B 10 by removing the hand set comprising the transmitter 63^b and the receiver 64^b from its supporting cradle to permit the plunger of the switch 72^b to be moved from its normal position to its first operating position. The switch 72^b responds to 15 this movement of its operating member by moving the spring 32^b from engagement with the spring 33^b to open a further point in the above-traced circuit for energizing the signal device 66^b. Also, the spring 32^b is moved into engagement 20 with the spring 31^b to connect the battery 73 to the line 61 through the windings of the impedance element 74^b. Thus, the lower terminal of the battery 73 is connected by way of the conductor 76 and the lower winding of the element 25 74^b to the line conductor 61^a of the line 61, and the upper terminal of the battery 73 is connected by way of the conductor 75, the upper winding of the element 74^b and the springs 31^b and 32^b to the opposite line conductor 61^b. The springs 30^b 30 and 27^b are respectively operated into engagement with the springs 29^b and 28^b in response to the operation of the switch 72^b resulting from removal of the hand set from its supporting cradle. At the last-mentioned springs, the two terminals 35 of the subset comprising the transmitter 63^b and the receiver 64^b are connected, respectively, to the line conductors 61^a and 61^b of the line 61. It will be noted that the circuit over which the subset is connected to the line 61 is independent 40 of the position of the line selecting switch 65^b, the arrangement being such that the subset is always connected to the line corresponding to the station B when the hand set is removed from its supporting cradle. Following the operation of 45 the switch 72^b in the manner just described, the desired conversational circuit is fully completed.

It will be noted that, when the above-described call to the substation B is answered at this station, the operating circuit for the signal device 50 66^b is opened at the springs 32^b and 33^b of the switch 72^b and is held open for the duration of the call. On the other hand, the switch 72^a provided at the calling station A is operated to its last intermediate position so that the operating 55 circuit for the signal device 66^a provided at this station is prepared at the closed springs 32^a and 33^a. Thus, the station A may be signaled even though the apparatus provided at this station is being used to communicate over an established 60 connection. More particularly, to energize the signal device 66^a, it is only necessary to connect the conductor 78 to the conductor 60^b of the line 60 corresponding to the station A. Such a circuit may be completed to cause the energization 65 of the signal device 66^a so long as the springs 32^a and 33^a are in engagement. Hence, it will be seen that the station A may be signaled on an incoming call even though the apparatus embodied therein is being used on a call to another 70 station. With the switch 72^a arranged in the manner described, it is possible for the calling party at the station A selectively to connect the transmitter 63^a and the receiver 64^a to be used in communicating over the line 61 extending to the 75 called substation B or to be used in communicat-

ing over the line 60 corresponding to the station A and utilized by the party who initiates the second call. Thus, if it be assumed that the calling party at the station A is conversing over the line 61 with the called party at the station B and the signal device 66^a operates to indicate that a call intended for the station A has been initiated at another station, the conversing party at the station A may, by momentarily depressing the plunger of the switch 72^a to its normal position 10 to release the locking means described above, cause the subset comprising the transmitter 63^a and the transmitter 64^a to be disconnected from the line 61 and connected to the line 60. More particularly, if the locking means of the switch 15 72^a is released and the plunger of the switch is permitted to return to its first operating position, the spring 27^a is moved from engagement with the spring 26^a and into engagement with the spring 28^a, the spring 31^a is moved from engagement with the spring 34^a and into engagement with the spring 29^a, and the spring 32^a is moved from engagement with the spring 33^a and into engagement with the spring 31^a. From an inspection of the drawings, it will be apparent that, 20 when the springs 27^a and 30^a are moved into engagement with the springs 29^a and 28^a, respectively, the transmitter 63^a and the receiver 64^a are connected to the line 60.

After acknowledging the second call, the party 30 at the station A may desire to continue his conversation with the party at the station B. To this end, the line selecting switch 65^a is left in the position corresponding to the station B and the plunger of the switch 72^a is again operated 35 to its lowermost or final position and then released, so that the locking means of the switch 72^a again restrains the contact controlling member of the switch in its final intermediate position such that the springs 27^a, 30^a and 32^a are again held in engagement with their respective associated springs 28^a, 34^a and 33^a. With the enumerated operating springs 27^a, 30^a and 32^a in this last-mentioned position, the transmitter 63^a 40 and the receiver 64^a are again connected to be 45 used in communicating over the line 61 corresponding to the station B. Obviously, by repeated operations of the plunger embodied in the switch 72^a, the transmitter 63^a and receiver 64^a may be transferred from one line to the other 50 at will.

To release the established connection extending between the stations A and B, it is only necessary 55 that the hand sets respectively provided at these stations be replaced upon their respective supporting cradles. When this is done, the springs of the two switches 72^a and 72^b are restored to the positions illustrated in Fig. 5 and corresponding to the respective normal positions of the switches. It will be observed that, with the 60 switch 72^a in its normal position, the spring 32^a is in engagement with the spring 33^a and all of the other springs are disengaged. Hence, the circuit for energizing the signal device 66^a is prepared and the subset comprising the transmitter 63^a and 64^a is disconnected from all of the lines extending between the several stations. Similarly, when the switch 72^b is restored to normal, the circuit for energizing the signal device 66^b is prepared at the springs 32^b and 33^b 70 and the subset comprising the receiver 64^b and the transmitter 63^b is disconnected from all of the lines extending to the contacts of the switch 65.

While there has been described what is at 75

present considered to be the preferred embodiment of the invention, it will be understood that various modifications may be made therein, and it is intended in the appended claims to cover all such modifications as fall within the true spirit and scope of the invention.

What is claimed is:

1. In a telephone system, a first telephone station including a transmitter and a receiver, a plurality of additional telephone stations, a plurality of lines individually corresponding to said stations and each extending between all of said stations, each of said lines being adapted to be used only on calls incoming to the corresponding station, said first station including a line selecting switch operable to a plurality of positions individually corresponding to said lines to select said lines for use on calls to the stations corresponding to said lines, a second switch provided at said first station and having a plurality of operating positions including a normal position, means responsive to operation of said second switch to one of its operating positions for connecting said transmitter and receiver for use in communicating over the line corresponding to said first station irrespective of the position of said line selecting switch at the time said second switch is operated, means responsive to operation of said second switch to another of its operating positions for connecting said transmitter and receiver for use in communicating over the line corresponding to the position of said line selecting switch, and means responsive to operation of said second switch to its normal position for disconnecting said transmitter and receiver from all of said lines.
2. In a telephone system, a first telephone station including a transmitter and a receiver, a plurality of additional telephone stations, a signal device at each of said additional telephone stations, a plurality of lines individually corresponding to said stations and each extending between all of said stations, each of said lines being adapted to be used only on calls incoming to the corresponding station, said first station including a line selecting switch operable to a plurality of positions individually corresponding to said lines to select said lines for use on calls to the stations corresponding to said lines, a second switch provided at said first station and having a plurality of operating positions, means responsive to operation of said second switch to one of its operating positions for connecting said transmitter and receiver for use in communicating over the line corresponding to said first station irrespective of the position of said line selecting switch at the time said second switch is operated, means responsive to operation of said second switch to a second of its operating positions for causing the operation of the signal device at the station corresponding to the position of said line selecting switch, and means responsive to operation of said second switch to a third of its operating positions for connecting said transmitter and receiver for use in communicating over the line corresponding to said last-mentioned station.
3. In a telephone system, a first telephone station including a transmitter and a receiver, a plurality of additional telephone stations, a signal device at each of said additional telephone stations, a plurality of lines individually corresponding to said stations and each extending between all of said stations, each of said lines being adapted to be used only on calls incoming to

the corresponding station, said first station including a line selecting switch operable to a plurality of positions individually corresponding to said lines to select said lines for use on calls to the stations corresponding to said lines, a second switch provided at said first station and having a plurality of operating positions, means responsive to operation of said second switch to one of its operating positions for connecting said transmitter and receiver for use in communicating over the line corresponding to said first station irrespective of the position of said line selecting switch at the time said second switch is operated, means responsive to operation of said second switch to a second of its operating positions for causing the operation of the signal device at the station corresponding to the position of said line selecting switch, means responsive to operation of said second switch to a third of its operating positions for connecting said transmitter and receiver for use in communicating over the line corresponding to said last-mentioned station, and means responsive to operation of said second switch to a fourth of its operating positions for disconnecting said transmitter and receiver from all of said lines.

4. In a telephone system, a first telephone station, a plurality of additional telephone stations, a signal device at each of said additional stations, each of said stations including a transmitter and a receiver, a plurality of lines individually corresponding to said stations and each extending between all of said stations, each of said lines being adapted to be used only on calls incoming to the corresponding station, a source of current adapted to be connected to any one of said lines for the purpose of energizing the transmitters used in an established connection including said one line, said first station including a line selecting switch operable to a plurality of positions individually corresponding to said lines to select said lines for use on calls to the stations corresponding to said lines, a second switch provided at said first station and having a plurality of operating positions, means responsive to operation of said second switch to one of its operating positions for connecting the transmitter and receiver at said first station for use in communicating over the line corresponding to said first station irrespective of the position of said line selecting switch at the time said second switch is operated, means also responsive to operation of said second switch to said one position for connecting said source to the line corresponding to said first station, means responsive to operation of said second switch to a second of its operating positions for disconnecting said source from the line corresponding to said first station and for causing the operation of the signal device located at the station corresponding to the position of said line selecting switch, and means responsive to operation of said second switch to a third of its operating positions for arresting the operation of said last-mentioned signal device and for connecting the transmitter and receiver at said first station for use in communicating over the line corresponding to the position of said line selecting switch.

5. In a telephone system, a first telephone station, a plurality of additional telephone stations, a signal device at each of said additional stations, each of said stations including a transmitter and a receiver, a plurality of lines individually corresponding to said stations and each extending between all of said stations, each of said lines be-

ing adapted to be used only on calls incoming to the corresponding station, a source of current adapted to be connected to any one of said lines for the purpose of energizing the transmitters used in an established connection including said one line, said first station including a line selecting switch operable to a plurality of positions individually corresponding to said lines to select said lines for use on calls to the stations corresponding to said lines, a second switch provided at said first station and having a plurality of operating positions, means responsive to operation of said second switch to one of its operating positions for connecting the transmitter and receiver at said first station for use in communicating over the line corresponding to said first station irrespective of the position of said line selecting switch at the time said second switch is operated, means also responsive to operation of said second switch to said one position for connecting said source to the line corresponding to said first station, means responsive to operation of said second switch to a second of its operating positions for disconnecting said source from the line corresponding to said first station and for causing the operation of the signal device located at the station corresponding to the position of said line selecting switch, means responsive to operation of said second switch to a third of its operating positions for arresting the operation of said last-mentioned signal device and for connecting the transmitter and receiver at said first station for use in communicating over the line corresponding to the position of said line selecting switch, and means responsive to operation of said second switch to a fourth of its operating positions for disconnecting the transmitter and receiver at said first station from all of said lines.

6. In a telephone system, a first telephone station, a plurality of additional telephone stations, a signal device at each of said additional stations, each of said stations including a transmitter and a receiver, a plurality of lines individually corresponding to said stations and each extending between all of said stations, each of said lines being adapted to be used only on calls incoming to the corresponding station, a source of current adapted to be connected to any one of said lines for the purpose of energizing the transmitters used in an established connection including said one line, said first station including a line selecting switch operable to a plurality of positions individually corresponding to said lines to select said lines for use on calls to the stations corresponding to said lines, a second switch provided at said first station and having a plurality of operating positions, means responsive to operation of said second switch to one of its operating positions for connecting the transmitter and receiver at said first station for use in communicating over the line corresponding to said first station irrespective of the position of said line selecting switch at the time said second switch is operated, means also responsive to operation of said second switch to said one position for connecting said source to the line corresponding to said first station, means responsive to operation of said second switch to a second of its operating positions for disconnecting said source from the line corresponding to said first station and for causing the operation of the signal device located at the station corresponding to the position of said line selecting switch, means operated when the call is answered at said last-mentioned station for arresting the operation of said last-mentioned

signal device and for connecting said source to the line corresponding to the position of said line selecting switch, and means responsive to operation of said second switch to a third of its operating positions for connecting the transmitter and receiver at said first station for use in communicating over the line corresponding to the position of said line selecting switch. 5

7. In a telephone system, a first telephone station, a plurality of additional telephone stations, a signal device at each of said additional stations, each of said stations including a transmitter and a receiver, a plurality of lines individually corresponding to said stations and each extending between all of said stations, each of said lines being adapted to be used only on calls incoming to the corresponding station, a source of current adapted to be connected to any one of said lines for the purpose of energizing the transmitters used in an established connection including said one line, said first station including a line selecting switch operable to a plurality of positions individually corresponding to said lines to select said lines for use on calls to the stations corresponding to said lines, a second switch provided at said first station and having a plurality of operating positions, means responsive to operation of said second switch to one of its operating positions for connecting the transmitter and receiver at said first station for use in communicating over the line corresponding to said first station irrespective of the position of said line selecting switch at the time said second switch is operated, means also responsive to operation of said second switch to said one position for connecting said source to the line corresponding to said first station, means responsive to operation of said second switch to a second of its operating positions for disconnecting said source from the line corresponding to said first station and for causing the operation of the signal device located at the station corresponding to the position of said line selecting switch, means operated when the call is answered at said last-mentioned station for arresting the operation of said last-mentioned signal device and for connecting said source to the line corresponding to the position of said line selecting switch, means responsive to operation of said second switch to a third of its operating positions for connecting the transmitter and receiver at said first station for use in communicating over the line corresponding to the position of said line selecting switch, and means responsive to operation of said second switch to a fourth of its operating positions for disconnecting the transmitter and receiver at said first station from all of said lines. 10 15 20 25 30 35 40 45 50 55 60 65 70 75 80 85 90 95 100

8. In a telephone system, a first telephone station including a transmitter and a receiver, a plurality of additional telephone stations, each of said stations including a signal device, a plurality of lines individually corresponding to said stations and each extending between all of said stations, each of said lines being adapted to be used only on calls incoming to the corresponding stations, said first station including a line selecting switch operable to a plurality of positions individually corresponding to said lines, a second switch provided at said station and having a plurality of operating positions, means responsive to operation of said second switch to one of its operating positions for connecting said transmitter and receiver for use in communicating over the line corresponding to said first station irre- 10 15 20 25 30 35 40 45 50 55 60 65 70 75 80 85 90 95 100

8. In a telephone system, a first telephone station including a transmitter and a receiver, a plurality of additional telephone stations, each of said stations including a signal device, a plurality of lines individually corresponding to said stations and each extending between all of said stations, each of said lines being adapted to be used only on calls incoming to the corresponding stations, said first station including a line selecting switch operable to a plurality of positions individually corresponding to said lines, a second switch provided at said station and having a plurality of operating positions, means responsive to operation of said second switch to one of its operating positions for connecting said transmitter and receiver for use in communicating over the line corresponding to said first station irre- 75

rality of lines individually corresponding to said stations and each extending between all of said stations, each of said lines being adapted to be used only on calls incoming to the corresponding station, said first station including a line selecting switch operable to a plurality of positions individually corresponding to said lines, a second switch operative to one position in response to removal of said receiver from its supporting element and manually operable to another position, means responsive to operation of said second switch to its one position for connecting said transmitter and receiver for use in communicating over the line corresponding to said first station irrespective of the position of said line selecting switch, and means responsive to operation of said second switch to its other position for connecting said transmitter and receiver for use in communicating over the line corresponding to the position of said line selecting switch.

14. In a telephone system, a first telephone station including a transmitter and a receiver, a supporting element for said receiver, a plurality of additional telephone stations, a plurality of lines individually corresponding to said stations and each extending between all of said stations, each of said lines being adapted to be used only on calls incoming to the corresponding station, a source of current adapted to be connected to any one of said lines for the purpose of energizing the transmitters to be used in communicating over an established connection including said one line, a switch operative to one position in response to removal of said receiver from its supporting element and manually operable to another position, means responsive to operation of said switch to its one position for connecting said transmitter and receiver for use in communicating over the line corresponding to said first station, means also responsive to operation of said switch to its one position for connecting said source to the line corresponding to said first station, and means responsive to operation of said switch to its other position for connecting said transmitter and receiver for use in communicating over a second of said lines.

15. In a telephone system, a first telephone station including a transmitter and a receiver, a supporting element for said receiver, a plurality of additional telephone stations, a signal device provided at each of said additional stations, a plurality of lines individually corresponding to said stations and each extending between all of said stations, each of said lines being adapted to be used only on calls incoming to the corresponding station, said first station including a line selecting switch operable to a plurality of positions individually corresponding to said lines, a second switch operative to one position in response to removal of said receiver from its supporting element and manually operable to a plurality of other positions, means responsive to operation of said second switch to its one position for connecting said transmitter and receiver for use in communicating over the line corresponding to said first station irrespective of the position of said line selecting switch at the time said second switch is operated, means operative in response to operation of said second switch to one of its other positions for causing the operation of the signal device provided at the station corresponding to the position of said line selecting switch, and means responsive to operation of said switch

to a second of its other positions for connecting said transmitter and receiver for use in communicating over the line corresponding to the position of said line selecting switch.

16. In a telephone system, a first telephone station including a transmitter and a receiver, a supporting element for said receiver, a plurality of additional telephone stations, a plurality of lines extending between said stations, a switch operative to one position in response to removal of said receiver from its supporting element and manually operable to another position, means responsive to operation of said switch to its one position for connecting said transmitter and receiver for use in communicating over one of said lines, and means responsive to operation of said switch to its other position for connecting said transmitter and receiver for use in communicating over a second of said lines.

17. In a telephone system, a first telephone station including a transmitter and a receiver, a supporting element for said receiver, a plurality of additional telephone stations, a plurality of lines extending between said stations, a signal device at each of said stations, a switch operative to one position in response to removal of said receiver from its supporting element and manually operable to a plurality of other positions, means responsive to operation of said switch to its one position for connecting said transmitter and receiver for use in communicating over one of said lines, means responsive to operation of said switch to one of its other positions for energizing over a second of said lines the signal device at a called one of said stations, and means responsive to operation of said switch to a second of said other positions for connecting said transmitter and receiver for use in communicating over said second line.

18. In a telephone system, a first telephone station including a transmitter and a receiver, a supporting element for said receiver, a plurality of additional telephone stations, a signal device provided at each of said additional stations, a plurality of lines individually corresponding to said stations and each extending between all of said stations, each of said lines being adapted to be used only on calls incoming to the corresponding station, said first station including a line selecting switch operable to a plurality of positions individually corresponding to said lines, a second switch operative to one position in response to removal of said receiver from its supporting element and manually operable to a plurality of other positions, means responsive to operation of said second switch to its one position for connecting said transmitter and receiver for use in communicating over the line corresponding to said first station irrespective of the position of said line selecting switch at the time said second switch is operated, means operative in response to operation of said second switch to one of its other positions for causing the operation of the signal device provided at the station corresponding to the position of said line selecting switch, means responsive to operation of said switch to a second of its other positions for connecting said transmitter and receiver for use in communicating over the line corresponding to the position of said line selecting switch, and means responsive to operation of said second switch to a third of its other positions for disconnecting said transmitter and receiver from all of said lines.
